UNITED STATES PATENT OFFICE.

ALEXANDER F. MELROSE AND HENRY B. VAN DEUSEN, OF PITTSFIELD,
MASSACHUSETTS.

APPARATUS FOR DYEING.

SPECIFICATION forming part of Letters Patent No. 603,915, dated May 10, 1898.

Application filed September 8, 1897. Serial No. 650,906. (No model.)

To all whom it may concern:

Be it known that we, ALEXANDER F. MELROSE and HENRY B. VAN DEUSEN, citizens of the United States, residing at Pittsfield, in the county of Berkshire, State of Massachusetts, have invented certain new and useful Improvements in Dyeing Apparatus, of which the following is a description, reference being had to the accompanying drawings and to the letters of reference marked thereon.

Our invention relates to apparatus for dyeing wool, cotton, shoddy, &c.

The objects of our invention are to provide a simple and economical dyeing apparatus in which a single spraying or circulation pipe will serve for a plurality of tanks, to provide an effective device for introducing dye into the circulation-pipe at the suction side of its forcing means or pump, to provide an improved suction-box and steam-head for the tank or vat, to improve the construction of the sprayer proper, to provide vertically movable covers for the tanks, and to provide the circulating-piping with steam and cold water connections to boil and cool the stock, respectively. These objects we accomplish by means of the mechanism illustrated in the accompanying drawings, in which—

Figure 1 is a side elevation of the apparatus, one tank and the part in the bottom thereof being shown in vertical section. Fig. 2 is a plan of the same, the false bottom of one tank being partially removed. Fig. 3 is a vertical section on line 3 3, Fig. 2, looking to the right. Fig. 4 is a detail view showing the suction-box in side elevation and plan. Fig. 5 is a side elevation of the suction-box with the steam-head in place. Fig. 6 is a plan thereof; and Fig. 7 is a transverse vertical section on line 7 7, Fig. 6.

A A' represent the dyeing tanks or vats, supported in any suitable manner, but preferably on masonry, as shown, in a lower room or chamber A² and extending up through the flooring of an upper chamber A³, as shown in Figs. 1 and 3. The tanks are provided with false bottoms formed of a central circular apertured plate a, supported by the legs or angle-bars a' and provided around its periphery with an annular groove, forming a supporting shoulder or flange a², which receives and supports the inner ends of the perforated

bottom-sections a³, while an annular ring a⁴ in the tank supports the outer ends of the said bottom-sections. This provides for the ready removal of the bottom-sections when cleansing of the tank requires it.

B are suction-boxes which are bolted at their outer open flanged ends to the interior of tanks and extend inwardly under the plates a, where they are provided in their bottoms with a circular opening b, having a surrounding flange b', as shown. This opening b is directly in the center of the tub, tank, or vat, and the flange b' is spaced above the bottom thereof, so as to provide for the inflow of the liquid equally from every direction.

B' B² are suction-pipes connected with the outer ends of the suction-boxes by suction-nozzles b' b², and provided with valves b³ b⁴, the stems of which extend up into the chamber A³, where they are provided with hand-wheels. These pipes B' B² are connected together beyond their valves by a short pipe b⁵, which in turn connects by a coupling b⁶ and elbow b⁷ with the inlet end of a rotary pump F or other suitable forcing device. A cold-water pipe B⁴ is coupled to the pipe b⁵ and has a valve B⁵, the stem of which extends up into chamber A³, where it is provided with a hand-wheel. The pump F is provided with a drip-valve for use in winter to allow all liquor to escape from the pump-casing.

B⁶ is a horizontal pipe extending between the tanks or tubs A A' in chamber A³ and connected at one end with the discharge side of the rotary pump F by an elbow B⁷. (See Fig. 3.)

E is a vertical pipe in chamber A³, connected at its lower end to the rear end of pipe B⁶ and provided at its upper end with the horizontally-swinging section E', connected thereto by the swiveled elbow E². The free end of the swinging section E' has a depending discharge-pipe E³, adapted to register with the center of every tank or tub A A', &c., when swung thereover. The lower end of the pipe E³ is provided with a horizontal flange or stay-plate e, through which pass the vertical bolts e', the lower ends of which support the horizontal foraminated spray plate or disk e².

E⁴ is a hood secured to pipe E³ above plate e and extends out beyond the periphery of the spray-plate e².

It will be seen, therefore, that when valves B⁵ b⁴ are closed and valve b³, for instance, open and the pump or other forcing device F set in operation the liquid will be drawn from the bottom of the tub or tank A, at the center thereof, through suction-box B, pipes B' b⁵ b⁷, and then discharged through pipes B⁶ E E' E³ upon spray-plate e², which will spray or distribute it evenly over the stock contained in the tank, this action being furthered by the hood E⁴, as shown in Fig. 1. It is obvious that by swinging the pipe E' over tank A' the liquid may be transferred from tank A thereto, when by closing valve b³ and opening valve b⁴ the dye liquid may be circulated through said tank A'. In order to heat the liquid in the tanks, we provide them with steam-heads G, which are in the form of a tubular fork and straddle the inner ends of the suction-boxes B, the latter being provided with end and side ears or lugs b⁹, to which are bolted the corresponding ears g on the heads G. (See Figs. 5, 6, and 7.)

The steam-head G (see Figs. 6 and 7) has an inlet g', intersecting its two branches g² g³, and these branches terminate in the discharge-nozzles g⁴, which open upwardly and incline toward each other at opposite sides of the opening b. G' are valved steam-pipes which enter the tanks below their false bottoms and are there connected to the inlet g' of the heads G. By this construction the dye liquor may be readily heated to the boiling-point, and as the steam enters the tub at the center and the nozzles are inclined toward each other the stock will not be rolled in the tank by the force of the steam. The liquor may be further heated by means of steam from a pipe H, provided with a nozzle h, which discharges forwardly into the pipe B⁶ at its elbow B⁷. (See Fig. 3.) This steam-jet will also act as an injector and assist in circulating the dye liquor through the circulating-pipes.

In order to supply additional dye to the liquor during the process of dyeing, we provide a dye-receptacle K, which is connected by a valved pipe k at its nozzle k' with the pipe b⁷, just in advance of the pump F or injector, so that the dye will be thoroughly incorporated or mixed with the liquor in passing through said pump. The receptacle K and its valve are within chamber A³.

A⁶ and A⁷ are the covers for the tanks A A' and are suspended and raised and lowered by any suitable mechanism—such, for instance, as the ropes, pulleys, and windlasses shown in Fig. 1, which are so well understood that further description is deemed unnecessary. The covers are provided at one side with a hooded opening A⁸ to permit them to pass down over the pipe E', as shown in Fig. 1.

The operation may be briefly stated as follows: The dye liquor is first prepared in the tub A or A' and heated by steam through head G, and the stock is then placed therein.

The liquor is circulated by means of the pump F and piping from bottom of tub to the sprayer, where it is evenly sprayed over the stock. Steam is then admitted through pipe H and nozzle h and properly regulated by the valve. The tub-cover is then lowered to keep in the heat and the circulation of the dye liquor is kept up till the liquor comes to a boil, when the cover may be raised and the stock examined to ascertain whether it is the right shade. If it is not, then open valve in pipe k and allow more dye to enter pipe b⁷ through dye-nozzle, so that it will be thoroughly mixed by pump before it reaches the stock. In dyeing black, for example, at least one-fourth of the strength is left in the liquor after the batch is dyed. To save this, swing the sprayer over tank A' and pump the liquor from tank A into tank A' and open valve in pipe k' to admit enough dye to bring the liquor up to the required strength, when another batch may be dyed. After a batch has been dyed in tub A and the liquor thus drawn off cold-water valve B⁵ is opened and the water pumped into tub A through the spray-hood, the water being warmed by steam entering through pipe H and nozzle h to keep cold water from coming in contact with the stock, which would render it harsh and "full" it, while warm water renders the stock soft and cools it evenly. This cooling off is done in order to keep or set the shade, which would grow darker if the stock remained hot.

All of the valves referred to except drip-valve f are operated from within chamber A³ at the same side of the tanks, and vertical pipe E is at the opposite side of the tanks out of the way of the operator.

Having thus described our invention, what we claim as new, and desire to secure by Letters Patent, is—

1. The combination with the dye tub or tank having a foraminated or reticulated false bottom, of circulation-piping for the dye liquor having a central discharge-sprayer over the upper end of the tub, and a central suction-box in the space between said false bottom and the tub-bottom: said box being closed at its top and open below to permit the liquid to flow therein from all directions, substantially as described.

2. The combination with the dye tub or tank having a foraminated or reticulated false bottom, of circulation-piping for the dye liquor having a central discharge-sprayer over the upper end of the tub and a suction-box in the space between the false bottom and tub-bottom: said box being closed at the top, open at the bottom and there provided with a depending flange the lower edge of which is located above the tub-bottom, substantially as described.

3. The combination with the tub or tank having a foraminated or intersticed false bottom, of a suction-box below having an inlet-opening in its bottom at the center of the tub, a steam-head on the said box and hav-

ing its discharge at the center of the tub, a supply-pipe for the head and a circulation-piping connected to said suction-box and provided at its discharge end with a spraying or distributing device over the tub; substantially as described.

4. The combination with a tub or vat and its foraminated or reticulated false bottom, of valved piping extending from the bottom of the tub over the upper end thereof and there provided with a spraying or distributing device, a pump for forcing the liquor through the piping, a valved cold-water pipe connected to the circulation-piping at the suction side of said pump, a steam-pipe discharging into the circulation-piping to heat the contents (liquor or cold water) and a steam-pipe discharging into the tub below its false bottom; substantially as described.

5. The combination with the tub or tank having a foraminated or reticulated false bottom, of a pump and piping for drawing the liquor from the bottom of the tub and distributing it over the upper end thereof, and a steam-pipe discharging forwardly into said piping at the discharge side of the pump to assist it as an injector and also heat the liquor; substantially as described.

6. The combination with the tub or tank having a reticulated or foraminated false bottom, valved circulation-piping extending from the bottom of the tub over the top thereof, and provided between its ends with a liquid-forcing device to cause a continuous circulation through the pipe and tank, and a dye-receptacle K having a valved connection k at its lower end with the circulation-pipe at the suction side of the forcing device to permit the dye to flow down into the pipe and be thoroughly mixed with the liquor by said forcing device; substantially as described.

7. A dyeing apparatus comprising a tank having a perforated or reticulated false bottom, a valved steam-pipe discharging into the tank below said false bottom, a circulation-pipe exterior to the tank, in communication therewith at the top and bottom and operating separately and independently thereof, a forcing device between the ends thereof, and a dye vessel K having a valved outlet k secured at its lower end to the circulation-pipe just in advance of the forcing device, the dye being adapted to flow by gravity from vessel K into the circulation-pipe and be mixed with the liquor by the forcing device; substantially as described.

8. A dyeing apparatus comprising a plurality of tubs having false bottoms, valved suction-pipes leading from the bottoms of said tubs, a pump to the inlet side of which said suction-pipes are connected, a discharge-pipe leading from the pump and provided with a vertical member having a horizontally-swinging section adapted to be swung over all of the tubs and there provided with a sprayer or distributor, steam-pipes discharging into the bottoms of the tubs to heat the contents,

a valved cold-water pipe connected to the piping at the suction side of the pump, a steam-pipe discharging forwardly into the piping at the discharge side of the pump and a dye-supply communicating with the piping at the suction side of the pump; substantially as described.

9. In a dyeing apparatus, a suction-box having an inlet-opening at the inner end of its bottom, and a steam-head on the inner end of the box and having upwardly-discharging outlets at opposite sides of said suction-box inlet; substantially as described.

10. In a dyeing apparatus a suction-box having an inlet-opening at the inner end of its bottom and provided on the outer sides of said end with apertured ears or lugs, and a forked or branched steam-head embracing the inner end of said box and having apertured ears or lugs registering with those on the box and bolted thereto, said head also having discharge openings or nozzles opening upwardly and inwardly at opposite sides of the suction-box inlet; substantially as described.

11. The combination with the tub having a foraminated or reticulated false bottom, of a suction-box secured to the tub under the false bottom and provided at the center thereof with a bottom inlet-opening, a circulation-pipe extending from the outer end of the suction-box up over the top of the tub, a forcing device between the ends of the circulation-pipe, a steam-head on the inner end of the suction-box and having discharge-nozzles opening upwardly and inwardly at opposite sides of the suction-box inlet, and a steam-pipe connected with said head; substantially as described.

12. A dyeing apparatus comprising a tub or vat, having a foraminated or reticulated false bottom and a suspended vertically-movable cover provided with a hooded side opening, a circulation-pipe extending from the bottom of the tub and provided with a horizontally-swinging member extending through said hooded top opening, a forcing device for the liquid in the circulating-pipe, and a steam-pipe discharging into the bottom of the tank to heat its contents; substantially as described.

13. The combination with the tank having a foraminated or reticulated false bottom, of a circulating-pipe connected with the bottom of the tank and having a horizontal section extending over the top of the tank and there provided with a depending pipe E³, a spray-plate suspended under the end of pipe E³ and a hood E⁴ secured to said pipe and extending out beyond the periphery of said spray-plate; substantially as described.

In testimony whereof we affix our signatures in presence of two witnesses.
